United States Patent Office

Des. 216,007

Patented Nov. 18, 1969

216,007

BOTTLE CAP

Patrick Kearney, 38-11 217th St.,
Bayside, N.Y. 11361

Filed Aug. 8, 1968, Ser. No. 13,064

Term of patent 14 years

Int. Cl. D9—02

U.S. Cl. D9—281

FIG.1

FIG.2

FIG.4

FIG.3

FIG. 1 is a top plan view of a bottle cap, showing my new design;

FIG. 2 is an elevational view, the opposite side being the same in appearance;

FIG. 3 is a bottom plan view; and

FIG. 4 is an elevational view looking from the right of FIG. 2, the opposite side being the same in appearance.

I claim:

The ornamental design for a bottle cap, as shown and described.
